CRACKING HYDROCARBON OILS

Luis de Florez, Pomfret, Conn., and James W. Gray, Lambertville, N. J., assignors to Gasoline Products Company, Inc., Jersey City, N. J., a corporation of Delaware

Application April 8, 1941, Serial No. 387,418

4 Claims. (Cl. 196—47)

This invention relates to the cracking of hydrocarbon oils for the production of gasoline or motor fuel.

The invention relates to certain novel improvements in the so-called black oil injection method of cracking. In this method of cracking a condensate oil is passed through a heating coil in a furnace in which coil the oil is subjected to high cracking temperatures, while a heavy stock such as a residual stock is injected into the latter portion of the heating coil and the resultant mixture subjected to conversion. In this type of operation it is desirable to subject the condensate oil in the first sections of the heating coil to relatively high cracking temperatures so that the condensate stock may be subjected to high rates of conversion to sustain reactions resulting in a production of high anti-knock gasoline. The black oil or heavy stock is injected into the latter sections of the heating coil with the idea that the high temperature condensate stream as well as the heat of the furnace will result in a mixture flowing through the latter portion of the coil at a temperature sufficient to effect a cracking of the mixture including the black oil but without coking. It frequently happens, however, that when the black oil is introduced into the high temperature stream coking difficulties have been encountered. It appears that when the black oil is introduced into the high temperature stream a completely homogeneous mixture is not produced immediately with the result that portions of the black oil are unduly heated by the high temperature stream as well as by the furnace and coking results.

In accordance with our invention the condensate stream undergoing high temperature cracking is removed from the furnace or heating zone and directed into a coil section outside the furnace or heating zone to which no heat is applied and the black oil is introduced into this outside section. A thorough mixing of the high temperature and black oil streams is accomplished in this outside section to produce a homogeneous mixture and the commingled oils are subjected to a period of soaking without the application of external heat to the coil. The mixture is then returned to the furnace or heating zone for completion of the cracking operation.

In one method of practicing the invention the high temperature stream which is directed into the outside soaking section is first contacted with a condensate stock or vaporizable oil and

the black oil is introduced into the resulting mixture in a subsequent portion of the outside soaking section, the black oil mixture being then delivered to a final section of the heating coil in the furnace.

For the purpose of more fully describing the invention reference is now had to the accompanying drawing which is a diagrammatic horizontal cross section of an apparatus adapted for practicing the invention.

In the drawing a heating apparatus of the well-known de Florez type is illustrated. While the practice of the invention is by no means restricted to this type of furnace, nevertheless, the de Florez method of heating is particularly advantageous in the practice of the invention. 10 represents the wall of a vertical furnace which may be suitably fired and provided with either down-draft or up-draft in the well known de Florez manner. As illustrated, the furnace is of the up-draft type and is provided with a bottom burner 11. Vertically disposed tubes are arranged adjacent the wall of the furnace so as to be heated preponderantly by radiant heat. 15 A primary row of tubes 12 is connected by alternate top and bottom headers or return bends to provide for series flow through the tubes. The condensate stock is introduced to the first tube of the series by means of an inlet pipe 13. 20 A transfer line 14 conducts the oil from the last tube of the row of tubes 12 to an outside row of tubes 15. The tubes 15 are disposed outside the furnace and are not subjected to any external heating means. The tubes are provided with alternate top and bottom headers or return bends to provide for series flow through the tubes. A line 16 is provided for introducing a condensate or vaporizable stock to the first tube of the outside row of soaking tubes. A line 17 is provided for introducing the black oil or residual stock to one of the subsequent tubes in the row of soaking tubes 15. A transfer line 18 serves to conduct the oil from the last tube of the row of soaking tubes 15 to the first tube of a second 25 or final series of tubes 19 disposed adjacent the furnace wall 10 and adapted to be heated preponderantly by radiant heat. This row of tubes is connected by alternate top and bottom headers to provide series flow through the row of tubes. 30 An outlet of transfer line 20 extends from the last row of tubes 19 to a suitable separator (not shown) for separating the cracked products into vapors and residue.

In practicing the invention the condensate stock 35 is charged through the inlet 13 to the first row

of tubes 12. This stock should be of a character adapted for high temperature or high cracking per pass cracking. Preferably, the distillation test of the stock as indicated by the standard A. S. T. M. Distillation Test D-86 should have a 90% point below 700° F. or below 650° F. The stock should have a color of or below 3.5 N. P. A. and usually of or below 2.0 N. P. A. The carbon residue of the stock as indicated by the A. S. T. M. D-189 test should be below 0.045% and usually 10 below 0.025%. The stock may be a recycle stock obtained in the fractionation of the cracked vapors or it may be a straight-run or cracked stock which is subjected to single pass cracking in the coil 11 or it may consist of a mixture of straight-run and recycle stock. The oil in transit through the tubes 12 is maintained under cracking conditions of temperature and pressure to effect the desired conversion. It is desirable to heat the oil in the coil 12 so that it is discharged from 20 the last tube of the coil through pipe 14 at a temperature in excess of 900° F. and preferably at temperatures of the order of 1000 or 1050° F. The pressure in the coil 12 should ordinarily be in excess of about 200 lbs. and usually is of the order of 400-800 lbs. The condensate introduced through line 16 is either recycle stock or condensate from an extraneous source and is introduced at temperatures preferably of 500° F.-700° F. The usual method of introducing the black oil through line 17 is to charge a residual stock such as topped or reduced crude into a primary dephlegmator of the system and use the resultant mixture of unvaporized charge and heavy reflux condensate as the stock which is injected through the line 17. In some cases the topped or reduced crude is drawn from the crude stills in a heated condition and passed directly through a line 17 to the coil 15. The black oil is preferably introduced at temperatures of about 600° F. or 700° F. or higher.

By reason of the change of direction in the flow of oil back and forth through the soaking tubes 15 a completely homogeneous mixture of the black oil with the products from the heating coil 12 is obtained before the mixture is passed to the final heating coils 19 in the furnace.

The heating apparatus specifically described herein is particularly adapted for providing an even heat distribution throughout the furnace so that the furnace temperatures applied to the heating coil 12 may approximate the temperature applied to the heating coil 19. However, the heat densities applied to the coil 19 will be lower than those applied to the coil 12, due to the higher temperatures of the oil in the coil 19. It is advantageous to apply lower heat densities to the final bank of tubes in which the final cracking is taking place.

In an example of the invention cycle condensate is subjected to cracking in the heating coil 12 and is passed through line 14 at a temperature of 1010° F. The cracked products are permitted to cool to a temperature of 990° F. before introducing the black oil. The black oil is introduced at a temperature of 700° F. and the mixture passes from the soaking and mixing tubes through the line 18 at a temperature of 875° F. The mixture is raised in temperatures in transit through the tubes 19 and is discharged therefrom at a temperature of 920° F.

In another example of the invention the cycle condensate is passed from the coil 12 through the transfer line 14 at a temperature of 1010° F., a small portion of the cycle condensate from the

bubble tower is injected through line 16 at a temperature of 670° F. to thereby reduce the temperature of the cracked products in coil 15 to 960° F. The black oil is introduced through line 17 at a temperature of 700° F. and the mixture is passed through line 18 at a temperature of 880° F. to the final heating bank 19 in which the temperature is raised to 930° F.

While we have described a particular embodiment of our invention for purposes of illustration, it should be understood that various modifications and adaptations thereof which will be obvious to one skilled in the art, may be made within the spirit of the invention as set forth in the appended claims.

We claim:

1. In the cracking of hydrocarbon oils the process that comprises passing a condensate stock through a heating coil in a heating zone, burning fuel to generate heat for the heating zone and applying the generated heat to said heating coil to subject the oil stream to a high cracking temperature, discharging the heated oil stream from the heating zone and passing it through a confined passageway in a cooling zone to thereby effect a reduction in the temperature of the oil stream, introducing a black oil stock into the cooled stream, passing the resultant mixture through a confined passageway with successive changes in the direction of flow to thereby produce therein a homogeneous mixture while continuing the application of cooling to the confined passageway, passing the homogeneous mixture thence through a subsequent heating coil and applying generated heat thereto to raise the temperature of the oil stream and subject it to further cracking therein.

2. In the cracking of hydrocarbon oils, the process that comprises passing a condensate stock through a heating coil in a heating zone, burning fuel to generate radiant heat for the heating zone and applying resultant radiant heat to said heating coil to subject the oil stream to a high cracking temperature and subject it to cracking, discharging the heated oil stream from the heating zone and passing it through a confined passageway in a cooling zone to thereby effect a reduction in the temperature of the oil stream, introducing a black oil stock into the cooled stream, passing the resultant mixture through a confined passageway with successive changes in the direction of flow to thereby produce therein a homogeneous mixture while continuing the application of cooling to the confined passageway, directing the homogeneous mixture thence through a subsequent heating coil disposed in the aforesaid heating zone and applying radiant heat to raise the temperature thereof, and subjecting the oil to further cracking therein.

3. In the cracking of hydrocarbon oils the process that comprises passing a condensate stock through a heating coil in a heating zone, burning fuel to generate heat for the heating zone and applying the generated heat to said heating coil to subject the oil stream to a high cracking temperature, discharging the heated oil stream from the heating zone and passing it through a confined passageway in a cooling zone to thereby effect a reduction in the temperature of the oil stream, introducing a relatively cool condensate oil into said confined passageway to lower the temperature of the oil stream flowing therein, introducing a black oil stock into the cooled stream and passing the resultant mixture through

a confined passageway with successive changes in the direction of flow to thereby produce therein a homogeneous mixture while continuing the application of cooling to the confined passageway, passing the homogeneous mixture thence through a subsequent heating coil and applying generated heat thereto to raise the temperature of the stream and subject it to further cracking therein.

4. In the cracking of hydrocarbon oils the process that comprises passing a condensate stock through a heating coil in a heating zone, burning fuel to generate heat for the heating zone and applying the generated heat to said heating coil to subject the oil stream to a high cracking temperature and effect cracking, discharging the heated oil stream from the heating zone and passing it through a confined passageway in a cooling zone to thereby effect a reduction in the temperature of the oil stream but not below a 20

temperature within the cracking range, introducing a black oil stock into the cooled stream, passing the resulting mixture through a confined passageway with successive changes in the direction of flow to thereby produce therein a homogeneous mixture while continuing the application of cooling to the confined passageway to maintain the mixture flowing therein at a temperature below the maximum temperature in said heating coil but at a temperature within the cracking range so that cracking is continued in transit through said confined passageway, passing the homogeneous mixture thence through a subsequent heating coil and applying generated heat thereto to raise the temperature of the oil stream and subject it to further cracking therein.
